UNITED STATES PATENT OFFICE.

FREDERICK W. LINAKER, OF DUBOIS, PENNSYLVANIA, ASSIGNOR TO THE VULCAN SOOT CLEANER CO., OF PITTSBURG, PA., OF DUBOIS, PENNSYLVANIA, A CORPORATION OF NEW JERSEY.

SOOT-CLEANER FOR BOILERS.

1,167,766.

Specification of Letters Patent. Patented Jan. 11, 1916.

Application filed May 20, 1915. Serial No. 29,336.

To all whom it may concern:

Be it known that I, FREDERICK W. LINAKER, a subject of the King of England, residing at Dubois, in the county of Clearfield 5 and State of Pennsylvania, have invented certain new and useful Improvements in Soot-Cleaners for Boilers, of which the following is a specification.

This invention relates to new and useful 10 improvements in soot cleaners for boilers, and especially boilers of the vertical tube type, such as the Wickes boiler.

An object of the invention is to provide a soot cleaner for vertical tube boilers that 15 is adapted to use a cleaning medium such as steam or gaseous fluid, and wherein the distributing pipe for the same is normally retracted from the heat zone of the boiler.

A further object of the invention is to 20 provide a soot cleaner for multi-tubular boilers in which the distributing pipe for spraying the cleaning fluid is moved to operative position between chosen tubes of the boiler, by the cleaning fluid, the distributing 25 member to be returned to a retracted position by the same supply of cleaning fluid.

With the above general objects in view and others that will appear as the nature of the invention is better understood, the same 30 consists in the novel construction, combination and arrangement of parts to be herein-after more fully described and then claimed.

In the accompanying drawings which 35 show the preferred embodiment of the present invention and to which reference is had herein by like characters designating corresponding parts throughout the several views: Figure 1 is a vertical sectional view of a portion of a vertical water tube boiler 40 of the Wickes type, with the present invention attached thereto. Fig. 2 is a horizontal sectional view of the same. Fig. 3 is a longitudinal sectional view of one of the cleaner elements. Fig. 4 is a cross-sectional view 45 taken on line IV—IV of Fig. 3. Fig. 5 is a cross-sectional view taken on line V—V of Fig. 3. Fig. 6 is a cross-sectional view taken on line VI—VI of Fig. 3, illustrating the spider connection between the operating rod 50 and the piston. Fig. 7 is a detail plan view of the check valve that is positioned within the piston and carried by the operating rod. Fig. 8 is a detail plan view of the removable 55 closure for one end of the piston, and Fig. 9 is an end elevation of the collar mounted on

the operating rod between one end casting and the hollow piston.

The present invention aims to provide a soot cleaner for water tube boilers and especially vertical tube boilers of the Wickes 60 type, in the form of cleaning members carried by the casing wall of the boiler and suitably positioned so that the distributing pipes for the cleaning fluid, when projected into the space between chosen tubes of the 65 boiler, will clean the entire exterior surfaces of the water tubes, and soot or other coating adhering thereto will be effectively removed. It is a well known fact that fire and products of combustion passing over water tubes 70 leaves a soot and incrustation thereon which has a deleterious effect on the boiler tubes and tends materially to shorten the life and use of the same. A boiler of the type shown in the present application and having attached thereto the cleaning elements to be hereinafter more specifically described, can be readily cleaned so that the exterior faces of the tubes will be freed from incrustations, etc., while the boiler is in operation, 75 one of the principal objects of the present invention being to provide a cleaner which may be operated while the boiler is otherwise in use.

In describing the invention in detail, and referring more particularly to Fig. 1 of the drawings, there is shown a water tube boiler of the vertical type and known in the trade as the "Wickes" boiler, the same including the outer casing or wall 10 communicating with the off-set fire box 11 while the vertical water tubes 12 are positioned within the casing 10. The tubes 12 are connected at their lower ends in the usual manner to a water drum while the upper ends thereof communicate with a steam dome 13. As clearly shown in Figs. 1 and 2, there is provided a central baffle wall 14, which is positioned centrally of the tubes 12 and terminates at its upper end at a point spaced below the steam dome 13, thereby to provide a space for the heat and products of combustion issuing from the fire box 11 to pass to the other side thereof through the space provided between the upper end of the 95 same and the said steam dome. These parts are elements contained in a Wickes vertical water tube boiler and form no part of the present invention.

The products of combustion and flames 100

from the fire box 11 cause a coating of soot and incrustations to be deposited and formed on the tubes 12, and the cleaners for removing this coating are mounted in the casing 10 and suitably positioned thereabout, each cleaner being designated in general as 15. The cleaning fluid for removing the soot from the tubes 12 may be either steam or gaseous fluid and I do not wish to confine myself to any particular fluid for cleaning the tubes, and for purposes of clearness, this fluid will be hereinafter referred to as "cleaning fluid". Two of the cleaning members are preferably positioned on opposite sides of the casing 10 and usually in vertical alinement, and the cleaning fluid is supplied thereto through the piping system shown in dotted line position in Figs. 1 and 2, the main feed 16 being controlled by a valve 20 cut-off 17 and a main line 18, which communicates by branch pipes 19 with the pipes 20 forming communication between the vertically alined cleaners. A drip cup 21 and valve 21' are provided beneath the main fluid feed 16, so that in case steam is the cleaning fluid, the same may be run off for a period until a dry steam appears.

One of the cleaning members 15 is shown in detail in Fig. 3, and a complete description of one will suffice for the complete set. Each cleaner includes end castings 22 and 23 having opposed threaded openings into which are received the threaded ends of a connecting cylinder 24. The end casting 23 is embedded within the casing 10 of the boiler as shown in Fig. 1, while the adjacent end of the cylinder 24 is also received therein and constitutes a substantially rigid support for the cleaning member.

40 The distributing member for the cleaning fluid consists of a hollow piston 26 having a threaded opening at one end thereof into which is received a threaded cap 27 having a valve seat 28. The opposite end of the 45 hollow piston 26 is provided with the contracted threaded opening adapted to receive the threaded end of the tubular member 29 which constitutes the distributing pipe for the cleaning fluid, the other end of the 50 distributing pipe being closed as by a removably threaded plug 29'. The outer end of the casting 23 is provided with a contracted opening 30 and an inwardly-directed shoulder 31 slightly spaced from the outer 55 end to provide suitable guides and supports for the distributing pipe 29, as is clearly indicated in Fig. 3. An annular groove is provided in the exterior wall of the hollow piston 26 and has packing rings 32 positioned therein and adapted to wipe the inner 60 face of the cylinder 24 to prevent the fluid in the barrel 25 from passing to either side thereof.

65 A threaded opening 33 is provided in the casting 22 and into which the fluid supply

pipe 20 is introduced and controlled by the valve 34, more clearly shown in Fig. 2. An operating rod extends through an opening provided in the outer end of the casting 22 and projects inwardly through the hollow piston 26 and into the distributing pipe 29, that portion of the operating rod which lies within the casting 22 and projects outwardly thereof when the distributing pipe 29 is in operative position, being circular in cross-section as indicated at 34, while the forward end of the rod is rectangular in cross-section as indicated at 35. A circular enlarged head 36 is carried by the extreme inner end of the operating rod and is slightly smaller in 70 diameter than the interior of the said distributing pipe. A packing gland 37 surrounds the cylindrical portion 34 of the rod and prevents the escape of the cleaning fluid from the casting 22 through the opening in 75 which the rod operates. The inner wall of the hollow piston 26 carries a spider frame 38 having a square opening adapted to receive the squared portion 35 of the operating rod. Spaced lugs 39 are carried by one 80 side face of the spider 38 and are adapted to engage the rear wall of the check valve 40, this valve being in the form of a disk ring having a square opening adapted to be loosely supported on the squared portion 35 85 of the operating rod and adapted in its operation to engage the valve seat 28 in the closure cap 27 in a manner to be hereinafter more clearly stated. The cylindrical portion 34 of the operating rod that extends within 90 the casting 22 has a collar 41 mounted thereon and held in fixed position by the set screws 42, there being an enlarged head 43 carried by said collar and adapted to be engaged by the rear end of the hollow piston. 100

The upper end of the casting 22 has secured thereto a hood section 44 which carries a projecting portion 45 adapted to overlie the circular portion of the rod 34. Means are provided which will indicate when the 110 distributing pipe is in proper position between the tubes of the boiler and consists of an indicator or tell-tale device which includes a collar 46 secured to the rod 34 and so positioned thereon as to lie beneath the 115 hood extension 45 when the distributing pipe is in its operative position. The handle 47 is secured to the extreme outer end of the operating rod, and by which the said rod may be revolved for imparting such movement to the distributing pipe. 120

To cause the distributing pipe 29 to be positioned between the tubes 12 of the boiler and for supplying the same with cleaning fluid for removing the soot and other incrustations from the water tubes, the controlling valve 17 shown in Fig. 1 is opened and the cleaning fluid passes through the main supply pipe 16 into the main branch 125 18 and is fed therefrom through the sub- 120

branches 19 into the pipes 20. The controlling valves 34 may then be opened to permit the cleaning fluid to pass into the casting 22 and this cleaning fluid being fed under pressure, causes the piston 26 to move within the cylinder 24 to a point adjacent the extreme end thereof, at which time the compression coil spring 48 is engaged and cushions the further forward movement of the piston and thereby obviates injury to the moving parts, and will also cause the piston to come to a gradual state of rest. The spring 48 surrounds the distributing pipe 29 and normally engages at one end the annular shoulder 31 on the inner wall of the casting 23. When the piston moves forwardly as above indicated, the distributing pipe 29 is projected through the casting 23 and between chosen tubes of the boiler, and is guided by the squared portion 35 of the operating rod in combination with the spider 38 of the said piston. The operating rod is held normally at its extreme outer position so that the outer end of the collar 41 engages the adjacent end wall of the casting 22, and the rod remains normally stationary until the spider 38 carried by the movable piston engages the enlarged circular head 36 on the said rod, and at this time further movement of the piston caused by the pressure of the cleaning fluid will move the said rod, and cause the collar 46 to move beneath the hood extension 45, which will indicate that the distributing pipe is in correct position between the tubes for operation. Suitably-disposed radial openings 49 are provided in the distributing pipe 29 and the cleaning fluid is caused to issue therefrom in jets that describe a circular path. The cleaning fluid is permitted to pass through the cap 27 in the end of the hollow piston, and thereafter enter the distributing pipe, and when the handle 47 is revolved, such movement is imparted to the distributing pipe 29 by the spider 38, and squared portion 35 of the operating rod, it being noted that the distributing pipe is fixed to the hollow piston and moves therewith.

By controlling the direction of travel of the cleaning fluid, the same may be shut off from the casting 22 and fed to the casting 23 at the forward side of the piston 26 to cause the piston and distributing pipe carried thereby to be retracted to its normal inoperative position, or with the distributing pipe out of the heat zone of the boiler and positioned remote from the boiler tubes within the cylinder and castings. This operation is afforded by the by-pass 50 in the supply pipe 20 and controlled by the valve 51, the by-pass communicating with the fluid pipe 52 that is held and supported by the end castings 22 and 23, there being provided an apertured lug 53 on the forward upper

end of the casting 22 through which the said pipe 52 extends, while the same is threaded at its opposite end into the casting 23 as at 54. A fluid passage 55 is provided in the upper side of the casting 70 23 and communicates at one end as at 56 to the inner wall of the casting at a point adjacent the shoulder 31 and in rear of the extreme forward movement of the piston 26. By operating the valves as above stated, the 75 cleaning fluid is shut off from the casting 22 and directed into the pipe 52 and passage 55, the said fluid engaging the forward end of the piston 26 to move the same rearwardly, and thereby draw the distributing 80 pipe 29 into the cylinder and castings. When the distributing pipe is drawn into these parts, the cleaning fluid that is caused to retract the piston will pass through the openings 49 into the interior of the distributing pipe and hollow piston 26, and in endeavoring to escape through the cap 27 of the piston, will force the check valve 40 on to the seat 28 and thereby shut off the escape of the cleaning fluid and further 85 insure a positive retracting movement of the piston and distributing pipe. The operator may readily determine when the distributing pipe is completely within the outer end of the casting 23 by the indicating ring 46, 90 the same being projected from beneath the hood extension 45 by the piston cap 27 engaging the enlarged head 43 of the collar 41, which will move the said collar and operating rod through the packing gland 37. 95

It is believed that the operation of the device will be readily apparent from the above detailed description of the same, and it is to be noted that the fluid utilized for removing the soot, and incrustations from the exterior walls of the water tubes is also used as the power means for projecting the cleaning or distributing pipe into spaces between chosen tubes, and wherein the fluid is also used to retract the distributing pipe. 100

The drawings show the preferred embodiment for carrying my invention into effect, but I do not wish to confine myself to the details shown, as various changes may be made without departing from the spirit and scope of the invention and which will fall within the scope of the appended claims. 105

What I claim as new is:—

1. A soot cleaner for water tube boilers, including end castings and a connecting cylinder, a hollow piston and distributing pipe carried thereby reciprocable in said cylinder and castings, an operating rod extending into said piston and distributing pipe, fluid-operated means for moving the piston and distributing pipe in either direction, and indicating means for determining when the distributing pipe is within the connecting cylinder and castings. 115

2. A soot cleaner for water tube boilers 120

65

125

130

comprising a cleaning device including a cylinder, a hollow piston and distributing pipe carried by said piston arranged within said cylinder, fluid supply means for each 5 end of the cylinder at opposite sides of the piston, an operating rod extending into said piston and distributing pipe, and a check valve supported on said rod adapted to be moved to engaging position with said piston 10 to prevent the escape of cleaning fluid therethrough.

3. A soot cleaner for water tube boilers comprising a cleaning device including end 15 castings, and a connecting cylinder, a hollow piston within said cylinder, a distributing pipe carried by said piston, an operating rod including a portion angular in cross-section slidably extending into one of 20 said castings, the piston and the distributing pipe, connecting means between the angular portion of the operating rod and the piston whereby the same are caused to rotarily move in unison, coöperative valve mechanism carried by the piston and angular portion 25 of the rod, and valve-controlled fluid supply pipes connected to each casting whereby the piston is caused to move in opposite directions.

4. A soot cleaner comprising an inclosing 30 housing, a piston including a valve seat and a distributing pipe carried thereby and slidably arranged within said housing, fluid supply means for each end of the housing, an operating rod associated with said piston 35 whereby when the distributing pipe is projected from the housing, the same may be rotated by said rod, and a valve carried by said rod adapted to engage the piston valve seat to prevent the escape of fluid there- 40 through.

5. A soot cleaner for water tube boilers including an inclosing housing, a distributing pipe arranged within said housing, a member having an opening therein connected to 45 said distributing pipe, an operating rod received in said opening in the member, an enlarged head carried by the extreme inner end of said operating rod, an indicating device carried by said rod exteriorly of the 50 housing, and means for moving said distributing pipe exteriorly of said housing and to a position to cause said member to engage the enlarged head on the operating rod to move said rod to a position whereby 55 the indicating device will determine when the distributing pipe is in operative position.

6. A soot cleaner for water tube boilers comprising a housing, a distributing pipe arranged within said housing, means within 60 the housing coöperating with the distributing pipe for projecting and retracting the same into operative and inoperative positions, and independently operating means slidably associated with the distributing 65 pipe for rotating the same.

7. A soot cleaner for boiler tubes comprising a housing, a hollow piston and distributing pipe carried thereby and slidably disposed within said housing, an operating rod having a portion angular in cross-section 70 slidably associated with said piston, whereby when said piston and distributing pipe are projected, the same may be revolved, a collar secured to said operating rod and arranged within said housing, 75 whereby when the piston and distributing pipe are retracted the said collar is engaged thereby to move outwardly the operating rod to indicate that the distributing pipe is within the housing. 80

8. A soot cleaner for the water tubes of a boiler including a housing, a piston and distributing pipe carried thereby arranged within said housing, an operating rod carried by said housing and extending into said 85 piston, a tell-tale device carried by said rod and arranged exteriorly of said housing, and means carried by said rod within said housing adapted to be engaged by said piston to cause the said rod to move longitudinally to expose the tell-tale device to indicate that the distributing pipe is in retracted inoperative position. 90

9. A soot cleaner for boiler tubes including end castings, a connecting cylinder 95 therefor, a hollow piston slidably-mounted in said cylinder, a distributing pipe provided with radial openings carried by said piston, a spider having a square opening carried by said piston, an operating rod including a squared portion adapted to be received in said spider opening, a cap for one end of said piston provided with a valve seat, a disk valve having a squared opening 100 slidably-mounted on said operating rod and adapted to be moved to engaging position with the valve seat, and fluid supply means for each casting to cause the said piston to move in either direction. 105

10. Means for cleaning boiler tubes including a cylinder, a piston reciprocating therein, a distributing pipe carried by said piston and adapted to be projected from said cylinder into the space between the boiler tubes, an operating rod extending 110 into said piston and distributing pipe, a connection between said rod and piston whereby the piston may have free longitudinal movement with respect to said operating rod and also caused to rotate in unison with said 115 rod, coöperative valve mechanism carried by said piston and operating rod, and a dual fluid supply system for said cylinder whereby the piston is caused to move in either direction. 120

11. Means for cleaning the tubes of boilers including a housing, a hollow piston and distributing pipe slidably mounted within said housing, there being radial openings in said distributing pipe, an operating rod 125

- having a portion thereof angular in cross-section slidably associated with said housing and piston, position indicating means for the pipe carried by the rod, coöperating 65
 5 means carried by the piston and rod whereby when the distributing pipe is projected, the operating rod may be moved inwardly and subsequently revolved to impart rotary movement to said distributing pipe, coöperating 70
 10 valve mechanism carried by the piston and rod, and fluid supply means for the housing, the said fluid adapted to escape through the openings in the distributing pipe.
 15 12. A soot cleaner for water tube boilers including a housing, a piston and distributing pipe arranged within said housing, an operating rod slidably associated with said piston and adapted to revolve the same and 80
 20 fluid supply means for each end of the housing whereby the piston and rod are reciprocated, a hood carried by the outer end of the housing, an extension carried by said hood adapted to overlie the outer projecting end of said operating rod, a collar secured to said operating rod exteriorly of said casting, whereby the position of the distributing pipe may be determined by the location of the collar with respect to the 90
 25 hood extension.
 30 13. A soot cleaner for water tube boilers comprising a cleaning member for the boiler tubes having the inner end mounted in the boiler casing, a piston and distributing pipe arranged within the cleaning member, an operating rod freely extending into said 95
 35 cleaning member and slidably associated with said piston and distributing pipe, fluid supply means connected to each end of the 100
 40 cleaning member whereby the distributing pipe may be projected into a space between chosen rows of tubes and subsequently rotated by said rod and retracted to inoperative position within said member, and co-operating indicating means carried by the rod and the outer end of the cleaning member to determine whether the distributing pipe is in projected operative or retracted 105
 45 inoperative position.
 50 14. A soot cleaner, comprising in combination with an inclosing housing, a distributing pipe carried thereby and adapted to be reciprocated therein and to be projected therefrom to cleaning position, and an indicating device made operative after the initial 110
 55 movement of the distributing pipe when the pipe reaches the extreme movement in opposite directions for indicating the position of the pipe with relation to the housing.
 60 15. A soot cleaner for boiler tubes including a housing, a piston and distributing pipe within the housing, means for reciprocating the piston and distributing pipe to project the pipe beyond the housing to tube 115
 cleaning position, and an indicating device made operative at a point adjacent extreme movements of the piston in opposite directions to determine the position of the distributing pipe.
 16. A soot cleaner for boiler tubes including an inclosing housing, a piston and distributing pipe arranged therein, and an indicating device made operative after the piston starts movement in either direction to determine the exact position of the distributing pipe. 75
 17. A soot cleaner including a distributing pipe movable to operative and inoperative positions, and means for indicating when the distributing pipe is in operative or inoperative position, the said means being rendered operable only after the start of movement of the distributing pipe.
 18. A soot cleaner for water tube boilers comprising a housing, a hollow piston and distributing pipe carried thereby slidably mounted in said housing, a valve seat formed at one end of said housing, an operating rod slidably extending into said housing, piston and distributing pipe and being formed angular in cross-section for a portion of its length, a valve slidably associated with said rod adapted to engage the piston valve seat, a spider carried by the interior walls of said hollow piston and spaced from the ends thereof, slidably received on the angular portion of said rod whereby the piston and distributing pipe may slide freely over said rod and rotate in unison therewith. 95
 19. A soot cleaner for water tube boilers comprising a housing, a piston and distributing pipe carried thereby slidably arranged in said housing, an operating rod extending into said piston and pipe, coöperative means carried by the piston and rod for limiting the outward movement of said pipe, and means carried by said rod adapted to engage said housing and be engaged by said piston for limiting the inward movement of said distributing pipe. 100
 20. A soot cleaner for water tube boilers including a housing, a piston and cleaning fluid distributing pipe carried thereby slidably mounted in said housing, there being radial openings in said pipe, fluid supply means for each end of the housing, an operating rod slidably associated with said piston and pipe adapted to revolve the same, coöperative valve mechanism carried by said piston and rod that is open when the distributing pipe is in projected position and automatically closed to cause the fluid pressure at one end of the housing to return the distributing pipe to inoperative position 120
 115
 120
 125
 21. A soot cleaner for water tube boilers including a housing, a piston and distrib-

utting pipe carried thereby slidably arranged in said housing, an operating rod slidably extending into said housing, piston and pipe, indicating means carried by said rod exteriorly of said housing and coöperating therewith for limiting the inward movement of the rod and for determining when the distributing pipe is in operative position, and means carried by said rod interiorly of said housing for limiting the outward movement of said rod for indicating when the pipe is in inoperative position.

22. A soot cleaner for water tube boilers including a housing, a piston and distributing pipe slidably arranged in said housing, an operating rod slidably associated with said housing, piston and pipe adapted to revolve the piston and pipe and indicate the position of the pipe relative to the housing, and independent means carried by said rod positioned interiorly and exteriorly of said housing adapted to engage the housing to limit the longitudinal movements of said rod.

23. A soot cleaner for water tube boilers including a housing, a piston and distributing pipe carried thereby slidably arranged in said housing, an operating rod slidably associated with said piston and pipe adapted to revolve the same, coöperative means carried by said piston and said rod adapted to limit the outward movement of the distributing pipe, and means carried by said rod interiorly of said housing to engage said housing and be engaged by said piston to

limit the inward movement of the piston and distributing pipe.

24. A soot cleaner for water tube boilers including a housing, a piston and distributing pipe carried thereby slidably arranged in said housing, an operating rod slidably associated with said piston and pipe adapted to revolve the same, coöperative means carried by said piston and said rod adapted to limit the outward movement of the distributing pipe, fluid supply means for each end of the housing, and coöperative valve mechanism carried by the piston and rod adapted to be closed during the retracting movement of the piston and pipe.

25. A soot cleaner for water tube boilers including a housing, a piston and distributing pipe carried thereby slidably arranged in said housing, an operating rod slidably associated with said piston for revolving the same, means carried by said rod interiorly and exteriorly of said housing adapted to engage the housing to limit the longitudinal movements of said rod, and means carried by said housing coöperating with the exteriorly positioned means on the rod for determining when the distributing pipe is in projected operative or retracted inoperative position.

In testimony whereof I affix my signature in presence of two witnesses.

FREDERICK W. LINAKER.
